(57) **CLAIM**

The ornamental design for a triple zone workstation, as shown and described.

DESCRIPTION

FIG. 1 is a perspective view of a triple zone workstation according to a first embodiment of my design, wherein vertically adjustable zones of the triple zone workstation are shown in a first adjustment configuration thereof;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the triple zone workstation of FIG. 1, wherein the vertically adjustable zones of the triple zone workstation are shown in a second adjustment configuration thereof;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a perspective view of the triple zone workstation of FIG. 1, wherein the vertically adjustable zones of the triple zone workstation are shown in a third adjustment configuration thereof;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The broken lines in the drawing illustrating display monitors supported by the triple zone workstation of the claimed design form no part thereof. A user of the triple zone workstation to provide environmental context for the claimed design forms no part thereof. All other broken lines illustrate portions of the triple zone workstation that form no part of the claimed design.
